UNITED STATES PATENT OFFICE.

EDWIN O. ABBOTT, OF CHICAGO, ILLINOIS, ASSIGNOR TO THE ABBOTT
MACHINE COMPANY, OF SAME PLACE.

CHECK-PROTECTOR.

SPECIFICATION forming part of Letters Patent No. 401,871, dated April 23, 1889.

Application filed March 19, 1888. Serial No. 267,762. (Model.)

To all whom it may concern:

Be it known that I, EDWIN O. ABBOTT, a citizen of the Dominion of Canada, residing at Chicago, in the county of Cook and State 5 of Illinois, have invented certain new and useful Improvements in Check-Protectors, of which the following is a specification, to wit:

My invention relates to improvements in check-protectors; and it consists in the construction, arrangement, and operation of the parts, as will be hereinafter fully described, and particularly pointed out in the claims.

To enable others skilled in the art to which my invention relates to make and use the 15 same, I will now proceed to describe my improvement, referring to the accompanying drawings, in which—

Figure 1 is a plan view. Fig. 2 is a central longitudinal section. Fig. 3 is a transverse section on $x-x$ of Fig. 1. Fig. 4 is a transverse section on $y-y$ of Fig. 1. Fig. 5 is an under plan view. Fig. 6 is a back view showing a modification of the stop p . Figs. 7 and 20 8 are views showing a modification of the block operating the punch-head, and Figs. 9 and 10 are views of another modification of the same device. Fig. 11 is a detail view of the block a^5 . Fig. 12, Sheet 4, is an enlarged view of the ratchet-wheels b^2 and b^3 , showing 25 one wheel broken away and the other behind it and showing the teeth of each inclined in the opposite direction. Fig. 13 is a vertical sectional view of the removable punches, showing connection with shank and special construction. Fig. 14 is a plan view showing rod n , spring m , and shaft H , and their relative location and arrangement. Fig. 15 is a view showing the form of irregular plate a^6 . Fig. 30 16 is a detail view of the spring-catch, showing the lip b^8 . Fig. 17 is an enlarged view of the ratchet-wheels, with one cut away, showing the irregular plate in position; and Fig. 18 is a detail sectional view of the knob of the crank-handle and its indicating-pin.

45 Similar letters refer to like parts throughout the several views.

A is the base or table, made of any suitable material, preferably of cast-iron. Upon this base is mounted a shell or casing, B, containing most of the working parts of my machine, made in any suitable form, but preferably of

the shape shown in the drawings. It is removably secured to the base by screws e , running into the body of the shell through the base from the bottom. 55

C is a dial-plate, removably attached by screws to the top of the shell B, and having on its face at proper intervals the figures 1, 2, 3, 4, 5, 6, 7, 8, 9, and 0, the dollar-sign, and asterisk, and having holes c opposite each figure and sign; or there may be any other figures or signs, as may be found necessary. I preferably form the inside surface of the dial-plate with a flange to hold it concentric with the shell, so that it will be held firm. Through 60 the center of the plate C passes a vertical shaft, a , journaled in said plate and in the base A. On this shaft at the top is a crank handle or lever, D, to revolve the shaft, this lever having a knob, b, having a pin, d, which 65 fits or drops into the holes c in the dial-plate or flange ring or band on top of the dial-plate. A small hollow post, r^5 , (see Fig. 18,) screws into the lever and knob. The knob fits over the same. The pin d , having the 70 collar v^4 , passes through the post and screws into the knob, with a spring, v^6 , interposed between the inner end of the post and the collar, so that the pin will drop or be forced 75 into the holes c , and may be withdrawn by 80 raising upon the knob in the act of changing the position of the lever.

The shell B on the inside has at one point a groove, f, running down preferably to a point on a line with the top of the double-flanged cylinder E. In this groove fits a tensioned block, g, which is riveted to a thin piece of spring-steel, h, whose end rests loosely on a shoulder, i, on the top of the hub F of the cylinder E, and held in position by a screw-nut, k, which screws onto the shaft a on top of the hub, and above this nut is a set-collar, l, on the shaft to hold the parts in position. The steel piece h is of sufficient strength to carry and return the block g immediately 90 upon being released a sufficient height to clear the punch-shanks. 95

Across the inside of the shell B near its top runs a horizontal shaft, H, journaled in both sides of the shell. On the end of the shaft on 100 the outside of the shell is a crank-handle, I, for oscillating the shaft. On the inside, rig-

idly secured to the shaft H, is a dog, K, over the block g, the dog K being made in such form that when the shaft is oscillated the dog will press down on the block g, so as to force down the punches under the block in a straight line, and thereby avoid the tearing of the check or paper while being punched or perforated.

The object of using the block g is to prevent the punch-cylinder from moving while the perforating is being done, which, if it did occur, the check or paper, being held firmly between the feed-rolls, would cause the perforations to be rough and unseemly. I find from experience that when the dog is operated in contact with the punch-shank without the intervention of the block the effect is to move the punch-cylinder a little, this being enough to make the perforations rough and unseemly and the check or paper liable to tear, the arc that the dog moves in being sufficient to cause this trouble, and I find that by using the block g between the dog and the punch-shank, and contacting with both, a direct and positive downward straight movement of the punch is insured and this difficulty overcome.

The shaft H has on it a spring, m, secured at one end to the shaft and running and resting upon and hooked over a rod, n, which runs through the shell near the top. This spring returns the shaft H to its normal position, carrying up with it the dog, allowing the block to be forced up and out of the way of the punch-shank. This spring has also the further duty to do—that is, the feeding. The upward momentum given to the shaft H by the spring m and the spring in the punch-shank is checked by the dog striking against the under side of the dial-plate, which will relieve the strain from the retaining-pawl of the feed mechanism which would otherwise occur, and thereby enables me to use a weak retaining-pawl, securing less friction and noise and better freedom for the parts to work.

In order to prevent the shaft H from moving too far down in its downward movement, and through the dog and block from forcing the punches too far down against the stripper-plate, and thereby injuring the parts, I provide on the crank-handle I a lug or projection, o, of appropriate length, which strikes against a projection or bracket, p, on the shell and limits the downward movement of the shaft and dog, and also prevents the pawl of the feed mechanism from engaging more than one tooth at a time in the ratchet, as presently explained.

Below the punch-cylinder and stripper-plate is a die-plate, L, which encircles the bottom of the shaft a and is fixed to revolve with said shaft, being held by means of the collar or plate q, which is rigidly secured to the shaft, a screw passing through the collar into the die-plate. On the lower face of the die-plate are duplicate figures and signs as

on the dial-plate; but their positions are in opposition to those on the dial-plate; those on the dial-plate being from left to right and on the die-plate being from right to left, or vice versa. These figures and signs are formed in the die-plate by a series of perforations for the passage of the punches. They, however, might be made solid signs or figures or otherwise, as desired.

Through the die-plate L are small holes r near the shaft, directly under similar holes, s, in the stripper-plate, through which holes in both plates pass dowel-pins, which are secured to the bottom face of the lower hub of the punch-cylinder.

The stripper-plate N is directly over the die-plate, with a space between sufficient to admit the insertion or withdrawal of the check or paper to be perforated. This plate surrounds the shaft a and revolves with it. This stripper-plate has through it and directly over it the same perforations of signs and figures as in the die-plate. These holes or perforations act as a guide for the punches and also to allow the punches to pass up without carrying the paper or check up with it or them. The dowel-pins before mentioned make both plates revolve with the shaft, as is evident.

E is a double-flanged cylinder or punch-disk having a top hub and bottom hub, F F, and a solid body having a groove, S', in its periphery, which forms top and lower flanges, t and u, the flanges having holes through which pass punch-shanks P, in number corresponding to the signs and figures in the die-plate. The punch-cylinder, main body, flanges, and hubs are preferably made in one solid piece, because of durability, cheapness, and convenience of construction.

P P are the punch-shanks or rods, which pass through holes in the flanges of the punch-cylinder and correspond in number with the figures and signs in the die-plate. The top of these shanks or rods in their normal position extend sufficiently above the flanges to be in proximity to the pressing-block g, operated by the dog K, so as to be readily pressed down when the shaft is oscillated. The lower ends of the punch-shanks are shouldered below the bottom flange, on which shoulder is riveted a small collar or disk, x. Between the flanges and surrounding each punch-shank is a spiral spring, a', which rests against the top surface of the lower flange, the spring at the top having a bearing against a small washer, a'', which is preferably loose on the punch-shank slightly below the under surface of the top flange, and held down by a pin, a', passing through the punch-shank and extending out a short distance beyond the periphery of the washer a'', for a purpose presently explained. The object of this spring is to draw the punches out of the paper and return the punches and punch-shanks to their normal position when the pressure is relieved.

R is what I call a "punch block or disk,"

made, preferably, of brass or any other suitable material. In this block are holes corresponding with the figures or signs below. Through these holes are inserted the punches 5 a^4 a^4 , which perforate the paper, the construction, arrangement, and connection of the punches with the punch-shanks being clearly shown in Fig. 13 of the drawings. The punch-disk R consists of a collar, x , which is riveted 10 to the punch-shank P, forming one body, and all together may be called a "punch," from which construction the office of the punch-shank is evident, and which construction I prefer. The block is secured by screws or 15 otherwise to the collar x , the screws passing into the block from above, so that the punches can be removed for repairs and for convenience in manufacture. These punches are preferably headed, so that they will not be 20 drawn out of the block, in case the punch should stick in the die-plate or paper below, and they are also prevented from being pushed or forced upward by fitting closely against collar x .

25 S is a block, preferably of an angle shape. It is fastened to the shell and passes through, extending beyond the inside wall of the same, at such a point so as to be opposite the punch that is to be operated. This block is provided 30 with a recess or slot, a^5 , to receive the pin a^3 of the punch shank or rod, the block S being placed at such a distance below the pin a^3 that when the punches are in their normal position the pin a^3 will pass over the 35 block in the revolution of the punch-disk; but when the punch is down the pin a^3 will rest inclosed in the slot a^5 and prevent the operator from revolving the punch-disk should the punch by any means stick in the 40 die-plate or paper below, thereby preventing the check or paper from being torn, which would otherwise occur if the cylinder could be revolved, the paper being held between the feed-rollers. So long as the pin rests in 45 the slot, the punch-disk cannot be revolved and no damage can be done to the check or to the several parts of the machine. The jarring of the handle will, in most instances, relieve the punch should it stick; but if that 50 be not sufficient, relief can be given by inserting an instrument between the stripper-plate and the punch-block R, an aperture, a^6 , being left in the shell for that purpose.

55 a^7 is an arm removably attached to the shaft II, near one end, the outer end of the arm being hinged to a connecting-rod, a^8 , which passes downward and is connected to an irregularly-shaped plate, a^9 , journaled upon the feed-shaft T, which runs through the 60 base, the shaft being journaled in a boxing near one end of the base at one end and at the other being journaled in a lever, X, whose purpose will be presently explained. The plate a^9 has attached at one end a small pawl, 65 b' , which engages the ratchet-wheel b^3 on the feed-shaft T on one side of plate a^9 . On the other side of plate a^9 is another ratchet-

wheel, b^3 , also on the shaft T. Both of said ratchet-wheels are removably yet rigidly attached to said shaft, the plate a^9 being held 70 in position laterally by the ratchet-wheels. The ratchet-wheels b^2 and b^3 have their teeth inclined in opposite directions, one from the other, as shown in Figs. 12 and, 17 of the drawings, the opposite inclination of the teeth 75 being for the purpose of holding the feed-roll fixed by means of the spring-catches b^5 and b^7 while the paper or check is being perforated. If it were not for this arrangement, the friction of the pawl b' upon the ratchet-wheel b^3 would cause the feed-roll to move 80 while the punch is in the paper, thereby making the perforations rough. The object of wheel b^3 is to hold the feed-roll from going too far when the feeding is being done, and is accomplished by means of the spring-catch b^7 dropping into the teeth, the projection b^9 on plate a^9 having passed upward so as to permit this, thus making the spaces between the figures or sizes uniform and equal. 85

90 b^4 is a post or projection from the base on one side of the shaft, to which is removably secured a small (preferably spring) pawl, b^5 , which engages the ratchet-wheel b^2 to prevent the feed-wheel from being moved backward 95 when the pawl b^5 is going downward to engage another tooth. On the opposite side of the shaft is another post or projection, b^6 , on which is removably secured a pawl, b^7 , preferably of spring-steel, whose end engages the 100 other ratchet-wheel, b^3 . This pawl is formed or provided with a lip, b^8 , which is engaged by a projection, b^9 , on the plate a^9 . The object of this pawl b^7 is to prevent the feed-wheel from being moved too far when the feeding 105 is done. The object of the lip or projection b^8 on said pawl is, that when it is engaged by the projection b^9 on the plate a^9 in its downward or backward movement, to disengage the end of said pawl b^7 from the ratchet-tooth in 110 wheel b^3 and to hold the pawl out of contact with said tooth of said wheel b^3 until the pawl b^7 has engaged a tooth in the ratchet-wheel b^2 , and in the upward or forward movement of the arm a^7 has revolved the ratchet-wheel b^3 115 and the feed-roll far enough for the point of the tooth in said wheel b^3 to have passed under the end of pawl b^7 . The projection b^9 on plate a^9 is so formed as to allow the point of pawl b^7 to drop into the next tooth, thus 120 securely locking the feed-wheel in one direction, and the pawl b^5 is so arranged as to have dropped into a tooth in wheel b^2 , thus securely locking the feed-wheel in the other direction, the objects of this construction and 125 arrangement being to hold the paper firmly and immovable while the perforating or punching is being done, and also to prevent overspacing should the operator allow the operating crank-handle to go upwardly too rapidly, or if it should slip from his hand and fly up. This will prevent irregular spacing. 130 If it were not for this, and irregular spacing occurred, there would be a possibility of in-

serting another figure or character between the ones already punched, making it easy to raise a check from the amount already originally punched in it, which is entirely overcome by the arrangement of the pawls and parts above described.

Near the front end of the feed-shaft T, on inside of base and shell and projecting through the base slightly above its upper surface, is removably secured a feed-roller, V, which revolves with the shaft and feeds the check or paper to be punched or perforated.

Removably secured to the outside of the shell by means of a bracket, c⁵, or otherwise, 15 is a pressure-roll, W, directly over the feed-roller V, journaled on a pin or rod in the bracket, so that when the feed-roller V revolves W will revolve also. By this roll the paper is held down on the feed-roll, and makes the feeding 20 uniform and on a straight line.

X is a lever hinged at one end a short distance from the feed-shaft and at right angles to it, the feed-shaft being journaled therein, the other end projecting through an aperture, 25 c', in the base, and it is provided with a thumb or flat surface to easily push down upon. To this lever is connected a spring, c², preferably underneath the lever. One end of the spring rests in the aperture c', for the purpose of 30 pressing the feed-roll V continuously against the pressure-roll W, for the purpose of feeding the paper and keeping it in proper position for perforating. In order to insert or withdraw the check or paper, I simply press 35 down upon the thumb-piece of the lever X, which will lower the roll V and permit the check or paper to be inserted or withdrawn, as the case may require.

It will be noticed that the front portion of 40 the shell at its lower edge, is slightly above the base, having an opening or slit, c', to permit the check or paper to be inserted between the stripper and die plates for perforating.

On both sides of the shell and on a line with 45 the end of the figures or signs to be operated in perforating and at right angles to the feed-shaft are placed two fingers or plates, c⁴, of any design or material, for the purpose of designating the line upon which the figures or 50 signs are to be perforated.

I prefer the manner of suspending the pressure-roll W by means of bracket c⁵, which bracket is removably secured to the shell, yet at the same time held rigid, in order that that 55 portion of the machine shall be secure from injury or destruction by anything falling on it, or from any other cause. It is evident that the pressure-roll might be suspended in any other suitable manner to accomplish the result desired.

In Figs. 7 and 8 of the drawings I have 60 shown a modification of the tenoned block g and its manner of being raised off the punch-shank after being released. The block g is angle shape, with the tenon c⁶ passing through a slot, c⁷, in the shell, having a cap, c⁸, screwed down securely by a screw, c⁹, on the tenon,

and projecting over the slot to hold said block in place and allow it to work up and down in the slot. The screw c⁹ passes through and projects beyond the inner surface of the vertical part of the block g, and is provided in this projection, on the lower side, with a groove or notch, e', in which rests and presses one end of a spring, c², the other end of the spring being secured to the adjustable screw-threaded rod n. The object of this spring is to return the block g to its normal position when the pressure is relieved, the object of the notch e' being to hold the end of the spring in its place, and by the tension of the spring in the notch the screw is kept from turning, thereby making it firm and free from liability of getting out of order. The tension of the spring is regulated by the rod n, one end of which is screw-threaded, the other having a slotted head for turning, and set-screw e', to hold it in position when the proper adjustment is obtained.

In Figs. 9 and 10 I have shown another 90 modification of the means of pressing down the punch-shanks in a straight line. Instead of the block, I provide a plate, g', preferably of spring-steel, one end being held in position by being removably attached to preferably a 95 bracket or projection, g', in the inside of the shell, the screw g', which secures it, being placed at a distance as far as can be obtained from the punch-shank to be operated, in order that the circle described by the free end of the 100 shoe may be as large as possible, so that in its downward movement the shoe will move in as nearly a straight line as possible. In these two modifications, as well as in the one shown in connection with the machine illustrated in 105 the drawings and first described, the downward movement of the block to contact with the punch-shank is caused by the pressure of the dog K, they being returned to their normal position by springs. I prefer in practice 110 to use the form and construction shown in Figs. 7 and 8 of the drawings.

It will be noticed that the dial-plate C, while removably secured to the shell by screws, is also at the same time rigid and stationary, 115 which is very important, in that the figures and signs are always in one place, so that the operator becomes familiar with their position, and in perforating the check or paper is less liable to err than he would be if it revolved, and the same care is not required to prevent mistakes.

In Fig. 6 of the drawings I have shown a modification for regulating the feed and punch mechanism. The lever which oscillates the 125 shaft is straight, and in connection with it is a bracket or plate on the outside of the shell, having two lugs at proper distance, between which the lever moves, its movement being limited by said lugs, which will regulate the 130 feed and punch mechanism.

The operation is as follows: The rolls are separated by pressing upon the thumb-piece of lever X, and the check or paper is then in-

serted between the rolls, as far through the slit into the machine as to place the line on which the figures are to be punched directly under the front edge of the indicating 5 brackets or fingers c^1 c^4 . The pressure is then released from the thumb-piece of the lever, and the check or paper will then be held firm between the rolls. I then take hold of the knob b , lifting it up, and turn the handle to 10 that figure or sign I wish to perforate, allowing the pin to drop into the hole c opposite said figure or sign. Then by pressing downward on the crank-handle I until the lug o has struck the stop or bracket p , the shaft 15 will be oscillated, and through the dog K and intermediate block g , press down the punches and perforate the check or paper. Then by allowing the handle to rise, which is done by spring m , the parts will be returned to their 20 normal position. While they are being returned, and after the punch has been withdrawn from the check or paper, the check or paper is fed by the other mechanism described, ready for another perforation. The same 25 operation is repeated as before, and so on until the requisite perforations are performed. The check or paper is then released by pressing upon the thumb-piece of lever X and withdrawn.

30 What I claim as new, and desire to secure by Letters Patent, is—

1. In a check-protector, the combination of a punch and oscillating lever for operating the punch, and a vertically-sliding block, G , 35 interposed between the lever and the punch, substantially as described,

2. In a check-protector, the tenen-shaped block g , having the cap c^1 , and screw c^2 , provided with a seat for the end of a spring, in 40 combination with the slotted shell B and spring c^2 , substantially as described.

3. In a check-protector, the combination of a movable cylinder, reciprocating punches carried thereby, a stop-pin, and the casing 45 having a slot, said pin and slot adapted to be brought into engagement with each other upon the movement of a punch, substantially as described.

4. In a feeding device for a check-protector, 50 the combination of a stationary feed-roll, a rotatable shaft fixed at one end and movable at the opposite end, a feed-roll mounted on the movable end of the shaft, and a lever engaging with the shaft for moving it to carry the feed-rolls from contact, substantially as described.

5. In a feeding device for a check-protector, 55 the combination of a stationary feed-roll, a rotatable shaft mounted at one end in fixed bearings, a feed-roll mounted upon the opposite end of the shaft, a lever carrying the latter end of the shaft, whereby to move it to carry its feed-roll from the stationary feed-roll, and a spring for normally holding the 60 feed-rolls in contact, substantially as described.

6. In a check-protector, the combination, with the feed-rolls, of two ratchet-wheels mounted to rotate together and having teeth oppositely arranged, a plate provided with a 70 projection and carrying an operating-pawl engaging with one of the said wheels, and a stop-pawl independent of the said plate, normally engaging with the other of the said wheels and arranged in position to be engaged by the projection of the said plate as it moves the pawl backward and to be disengaged by the said projection after the operating-pawl and the ratchet-wheel have partly completed their forward movements, whereby the said 80 stop-pawl is away from its ratchet-wheel at the commencement of the forward movement of the wheel, and is held away therefrom until the point of a ratchet-tooth has passed the point of the stop-pawl, but is permitted to engage with the wheel before it completes its forward movement, substantially as set forth.

7. In a check-protector, the combination, with the feed-rolls, of two ratchet-wheels mounted to rotate together and having teeth 90 oppositely arranged, a plate mounted between the ratchet-wheels and provided with a projection and carrying an operating-pawl engaging with one of the said wheels, and a stop-pawl normally engaging with the other of the 95 said wheels and provided with a projecting lip arranged in position to be engaged by the projection of the said plate as it moves the operating-pawl backward and to be disengaged by the said projection after the operating-pawl and the ratchet-wheel have partly completed their forward movements, substantially as set forth.

8. In a check-protector, the combination, with the feed-rolls, of the shaft T , carrying 105 one of the said rolls, the ratchet-wheels b^1 and b^2 , carried by the said shaft and having their teeth oppositely arranged, the plate a^9 , pivotally supported on the shaft and having the projection b^9 and the feed-pawl b' , and the 110 stop-pawls b^5 and b^7 , for the ratchet-wheels, the latter being arranged in position to be engaged by the projection b^9 on the plate a^9 when the latter is moved to carry the feed-pawl into its backward position, substantially as set 115 forth.

9. In a check-protector, the combination of the shell B , having stop or bracket p , the shaft U , having dog K , spring m , arm a^7 , connecting-link a^8 , plate a^9 , having projection b^9 , and crank I , having the lug o , and the rod n , all constructed, arranged, and operating substantially as shown and described, and for the purpose set forth.

In testimony whereof I affix my signature in 125 presence of two witnesses.

EDWIN O. ABBOTT.
